United States Patent Office

Des. 189,426
Patented Dec. 13, 1960

189,426

FINGER RING

Ben Axel, Kew Gardens, N.Y., assignor to Axel Bros.,
Inc., Jamaica, N.Y., a corporation of New York

Filed Aug. 2, 1960, Ser. No. 61,611

Term of patent 14 years

(Cl. D45—10)

FIG. 1

Fig. 1 is a top plan view of a finger ring showing my design;

Fig. 2 is a view in front elevation of the finger ring shown in Fig. 1; and

Fig. 3 is a view in side elevation of the finger ring shown in Fig. 1.

The dominant features of my design reside in the portions shown in full lines.

I claim:

The ornamental design for a finger ring, substantially as shown and described.
